ATTORNEY.

UNITED STATES PATENT OFFICE.

CHARLES L. WAGANDT, OF BALTIMORE, MARYLAND.

DESIGN FOR AN OIL-CAN.

SPECIFICATION forming part of Design No. 27,615, dated August 31, 1897.

Application filed April 5, 1897. Serial No. 630,866. Term of patent 7 years.

To all whom it may concern:

Be it known that I, CHARLES L. WAGANDT, a citizen of the United States, residing at Baltimore, in the State of Maryland, have invented and produced a new and original Design for Oil-Cans, of which the following is a specification.

Figure 1 is a front elevation of an oil-dispensing can, showing my design. Fig. 2 is a vertical section of the wall of the cylindrical can. Fig. 3 is a horizontal section of the wall of the can, shown on a larger scale.

The leading features of my design consist in the cylindrical surface, having vertical corrugations, with a horizontally-extending bead at the upper end and another at the lower end of all the corrugations, and a plain flat belt-like surface above the upper bead and another below the lower bead.

The can is cylindrical and its wall has verti-

cal corrugations *a*. At the upper end of all the corrugations is a bead *b*, extending horizontally around the can-wall, and at the lower end of said corrugations is a similar bead *b'*. A plain flat belt-like surface *c* is above the upper bead and extends around the cylindrical can, and a similar belt-like surface *c'* is below the lower bead.

The rounded or dome-shaped part at the top represents the cover of the can in its open position.

What I claim is—

The design for cylindrical vessels, substantially as herein shown and described.

In testimony whereof I affix my signature in the presence of two witnesses.

CHARLES L. WAGANDT.

Witnesses:

CHARLES B. MANN, Jr.,

CHAPIN A. FERGUSON.
